(57) **CLAIM**

The ornamental design for a tyre, as shown and described.

DESCRIPTION

FIG. 1 is a front, left side perspective view of a tyre showing my new design;

FIG. 2 is a front elevational view thereof;

FIG. 3 is a left side view thereof, the right side view being the mirror image thereof;

FIG. 4 is a partial front elevational view taken from FIG. 2 and shown in an enlarged scale;

FIG. 5 is a front elevational view highlighting a lateral segment of the claimed design;

FIG. 6 is a front elevational view highlighting the vertical central region of the claimed design shown circumferentially;

FIG. 7 is an enlarged fragmentary view showing laterally adjacent cleats and a channel between them; and,

FIG. 8 is a front elevational view highlighting the enlarged cleats and channel of FIG. 7.

The claimed element in FIGS. 5, 6, 7 and 8 appears in focus, while the remainder of each of the figures is purposely out of focus.
